TOY ELECTRIC RAILWAY

Ernst Beyer and Oswald Fischer, Nuremburg, Germany, assignors to Vereinigte Spielwarenfabriken Andreas Fortner & J. Haffner's Nachf. G. m. b. H., Nuremburg, Germany

Application April 14, 1938, Serial No. 202,107
In Germany January 20, 1938

14 Claims. (Cl. 213—212)

The invention relates to a remote-control coupling and uncoupling device incorporated in the track for toy electric railways, and consists in that an electrically actuated uncoupling device, 5 movably mounted in the body of the track on a rail, coacts with the coupling member of the vehicles.

The uncoupling device may consist, for example, of an electro-magnet interposed in the 10 main circuit, the armature carrying a lever which projects through the body of the track or the middle rail. The armature is preferably designed as a pivotally mounted bell-crank lever, the one arm of which serves as the armature, while 15 the other arm—designed as an oblique plane on both sides, in the longitudinal direction—projects, when the magnet is energised upwardly, through a slot in the middle rail, and lifts and 20 uncouples the coupling member of the vehicles running on the track.

The coupling member of the vehicles preferably consists of a rockable (e. g. pivotable) longitudinal link, which is provided, on the under 25 side, with a transverse bar, and, on sliding over the oblique surfaces of the armature arm projecting through the middle rail, is lifted and, by 30 means of a preferably integral transverse bow, disengages the coupling link of the one vehicle from the coupling hook of the other vehicle.

In the case of a toy railway equipped with the device designed in accordance with the invention, the coupled vehicles of a train can be uncoupled from the switchboard while running, by 35 actuating a switch before the vehicle to be uncoupled reaches that point on the track at which the electromagnet is installed. It is thus possible to couple and uncouple the vehicles, and also assemble a train in the manner usual in ordinary 40 railway practice. Consequently, a toy railway of this kind enables a highly diversified game to be played, thereby stimulating the imagination of the player, apart from the increased possibilities of the game. Particular importance attaches 45 to the possibility of uncoupling the vehicles in both directions of running. Thus, for example, a train which runs between two terminal stations and therefore changing its direction from time to time, can be uncoupled on each section of track.

50 The invention will be clearly understood from the following description aided by the accompanying drawing in which: a typical embodiment of the invention is illustrated and in which, Figure 1 is a view of a portion of the track 55 from below, Figure 2 is a side elevation of por-

tions of cars situated on the track, Fig. 2a is a side view and a longitudinal section through that part of the new device which is incorporated in the body of the track, Figure 3 is a plan of a portion of the track, and Figure 4 a plan of the coupling arrangement on the vehicles.

Arranged on the body *a* of the track are the two outer rails *b* and *b'*, and the middle rail *c*. Underneath, in the body of the track, is incorporated the electrically controlled switch device, which, in the embodiment shown, consists of an electromagnet *l*, *l'*.

The magnet armature *h* is formed by one arm of a bell-crank lever pivotally mounted at *f*, the other arm *e* of said lever, engaging in a slot *d* in the middle rail *c* and projects above the same (as indicated by broken lines in Figure 2), by means of a portion *g*, when the armature *h* is attracted by the magnet coil, that is to say, when 20 the electromagnet *l*, *l'* is switched into the circuit. That portion *g*, of the arm *e*, which projects above the middle rail, is provided, in the longitudinal direction with oppositely directed 25 oblique surfaces *g'* and *g*.

Engaging the armature *h* at *i* is a spring *k*, which returns the armature into the neutral position, and holds it there, when the current is cut off.

The electromagnet *l*, *l'* is preferably interposed in the main circuit. It is connected, on the one hand, with the contact spring *t* attached to the middle rail, by means of the cable *u*, and, on the other hand, by means of the cable *v* and clamp *m*, with the other pole of the source of current for the main circuit.

The cable *v* could also be connected to the live outer rail. The first named method is, however, preferable, since the voltage existing between the rails is liable to fluctuate owing to the varying speed of the vehicles.

When the lever arm *e*, *g* assumes the position indicated by the broken lines, and a train comes forward in the direction of the arrow *x*, the transverse bar *o* of the link downwardly extending pivoted longitudinal link *n* which engages the coupling hook *s* on both sides, slides over the oblique surface *g'* of the lever arm *e*, *g*, thereby swinging the link *n*—which is pivotally mounted 45 at *r*—into the position shown by the broken lines. At the same time, the coupling link *q*—which is connected (preferably integrally) with the longitudinal link *n* by a cross link *p*—is forced upwards, and therefore swung out of the coupling 50 55

hook s of the next vehicle, thus uncoupling the latter.

5 The cross link p engaging under the coupling link q , projects, by two lateral extensions p' , beyond this latter link on both sides, so that the coupling link q , when in the operative position, finds an abutment on the cross link p , which forces it upwards during the upward swing of the longitudinal link n .

10 The ends s' of the coupling hooks s slope upwards, so that, for coupling two vehicles together, the coupling link q of the vehicle w_2 slides automatically into the coupling hook of the vehicle w' , when the two vehicles come together.

15 As is evident from the drawing, the coupling members of all the vehicles of a train are alike. Each vehicle is provided with one set of such couplings in front and rear.

20 In order to illustrate the remote control system of applicants' invention Figure 1 shows diagrammatically a wiring diagram in which the electric leads U and V of a track section "A" are connected to a circuit 2. Any suitable source of power, such as battery 3 may be provided and 25 an ordinary switch 4 which may be mounted on a switch-board or any other remote point is also connected in the circuit. When it is desired to uncouple at a particular point in a train between two adjacent cars, the operator waits until the 30 coupling between the two adjacent cars to be uncoupled almost reaches the lever e at which time he depresses or actuates the electric switch 4 to close the circuit between the battery 3 and the electric magnet l and l' . This will immediately force the arm g upwardly so that it will 35 strike the first of the pair of uncoupling links n to uncouple one or both coupling links q . The uncoupled cars will stop and the remaining portion of the train will proceed further. As will be 40 noted in Figure 2a, the second following link n of the uncoupled car, when it reaches the oblique surface g' will force the lever g back down or will tend to stop the uncoupled car or cars if the 45 electric current is not of sufficient strength to overcome the inertia of the moving uncoupled cars. In any direction of movement of the train the leading uncoupling link n will always be located in the right direction to uncouple one or both coupling links q .

50 Having now particularly described and ascertained the nature of our said invention, and in what manner the same is to be performed we declare that what we claim is:

1. Remote-control uncoupling system for a 55 three-rail track, for toy electric vehicles, comprising an electrically actuated device having an electro-magnet mounted in the body of the track and means in the track operatively associated with the magnet to coact, when actuated by the magnet, with a coupling member of a vehicle, said means being composed of an armature for the electro-magnet having a lever secured thereto which is adapted to project above the middle rail of the track to contact a member of a vehicle to uncouple the latter, and means actuated from a remote point for energizing the electro-magnet.

70 2. Remote-control uncoupling system for a three-rail track, for toy electric vehicles, comprising an electrically actuated device having an electro-magnet mounted in the body of the track and means in the track operatively associated with the magnet to coact, when actuated by the magnet, with a coupling member of a vehicle, said means being composed of a pivotally mount-

ed bell-crank lever of which one arm serves as an armature and the other arm projects through a slot in the middle rail of the track when the armature is attracted by said magnet, and means actuated from a remote point for energizing the 5 electro-magnet.

3. Remote-control uncoupling system for a three-rail track, for toy electric railways, comprising an electrically actuated device having an electro-magnet mounted in the body of the track 10 and means in the track operatively associated with the magnet to coact, when actuated by the magnet, with a coupling member of a vehicle, said means being composed of a pivotally mounted bell-crank lever of which one arm serves as an armature and the other arm projects through a slot in the middle rail of the track when the armature is attracted by the magnet, and the lever arm projecting through the slot in the middle rail being provided with two oppositely 15 directed oblique surfaces to contact a member of a vehicle, and means actuated from a remote point for energizing the electro-magnet.

20 4. Remote control uncoupling system for a three-rail track, for toy electric railways, comprising an electrically actuated device having an electro-magnet mounted in the body of the track and means in the track operatively associated with the magnet to coact, when actuated by the magnet, with a coupling member of a vehicle, 25 said means being composed of a pivotally mounted bell-crank lever of which one arm serves as an armature and the other arm projects through a slot in the middle rail of the track when the armature is attracted by the magnet, a tension 30 spring of which one end is connected to the track and the other end to the armature of the bell-crank lever to return the lever to non-operative position, and means actuated from a remote point for energizing the electro-magnet. 40

5. Remote control uncoupling system for a three-rail track, for toy electric railways, comprising an electrically actuated device having an electro-magnet mounted in the body of the track and means in the track operatively associated with the magnet to coact, when actuated by the magnet, with a coupling member of a vehicle, 45 said means being composed of a pivotally mounted bell-crank lever of which one arm serves as an armature and the other arm projects through a slot in the middle rail of the track when the armature is attracted by the magnet, and a bar for each coupling member extending down toward the middle rail and being lifted by the second-mentioned arm of the lever to disconnect 55 the coupling of the one vehicle from the coupling hook of the adjacent vehicle, and means actuated from a remote point for energizing the electro-magnet.

6. Remote-control uncoupling system for a 60 three-rail track, for toy electric vehicles having coupling links and hooks, comprising an electrically actuated device having an electro-magnet mounted in the body of the track and having means in the track operatively associated with the magnet to coact, when actuated by the magnet, with an uncoupling member of a vehicle acting on the coupling links, the uncoupling device member consisting of, a downwardly extending pivotal longitudinal link having a member 65 extending around a coupling hook, which is adapted to engage under the coupling link, and means actuated from a remote point for energizing the electro-magnet. 70

7. Remote-control uncoupling system for a 75

three-rail track, for toy electric vehicles having coupling links and hooks, comprising an uncoupling device, an electrically actuated device having an electro-magnet mounted in the body 5 of the track having means in the track operatively associated with the magnet to coact, when actuated by the magnet, with the uncoupling device of a vehicle, the uncoupling device consisting of a downwardly extending pivotal longitudinal link having a member extending around 10 a coupling hook which is adapted to engage under the coupling link, and the member having lateral extensions which serve as an abutment for the coupling position but will swing said 15 link upwards, out of the coupling hook, during the act of uncoupling, and means actuated from a remote point for energizing the electro-magnet.

8. Remote-control uncoupling system for a three-rail track, for toy electric railways, comprising an electrically actuated device having an electro-magnet mounted under the body of and 20 between the two outer rails of the track and means in the track associated with the magnet to coact through the middle rail, when actuated 25 by the magnet, with a member of the vehicles to uncouple the latter, and means actuated from a remote point for energizing the electro-magnet.

9. Remote-control uncoupling device, incorporated in the track, for toy electric railways, 30 comprising an electrically actuated device having an electro-magnet mounted in the body of the track, means in the track associated with the magnet to coact, when actuated by the magnet, with a coupling member of the vehicles, said 35 means being composed of an armature for the electro-magnet having a lever secured thereto which projects through the track to contact the coupling member of the vehicles, and means for energizing said electro-magnet.

40 10. An uncoupling device for the coupling hook and coupling link of a toy railway car adapted to be actuated by a member in the track, comprising a trip device pivotally mounted on the car, said device having a downwardly extending

member and a part extending around both sides of the hook, said trip device when actuated by the member in the track by rotating the trip device around its pivot by means of the downwardly extending member, contacting and lifting 5 the coupling link from the coupling hook of an adjacent car by means of the part extending around the hook.

11. An uncoupling device according to claim 10 in which the part extending around both sides 10 of the hook constitute a pair of lateral extensions by means of which said part contacts and lifts the coupling link.

12. An uncoupling device according to claim 10, in which a lever arm is provided pivotally 15 mounted in the track which when actuated will rotate the downwardly extending member of the trip device to uncouple the cars.

13. In combination with a coupling hook and coupling link of a toy railway car adapted to be 20 actuated by a member in the track, an uncoupling device comprising a trip device pivotally connected on the car on the axis of the coupling link, said trip device having a downwardly extending member, and an arm at right angles 25 thereto and adjacent the hook whereby, when said downwardly extending member is actuated by the member in the track said arm will directly contact the coupling link to lift the latter from a coupling hook of an adjacent car. 30

14. Remote control uncoupling system, for a three-rail track, for toy electric railways, comprising an electrically actuated device having an electro-magnet mounted in the body of the track and means in the track operatively associated 35 with the magnet to coact, when actuated by the magnet, with a coupling member of a vehicle, said means being composed of an armature for the electro-magnet having a lever secured thereto which is adapted to project above the middle rail 40 of the track to contact a member of a vehicle to uncouple the latter.
